US0D1045837S

(12) **United States Design Patent** (10) **Patent No.:** **US D1,045,837 S**
(45) **Date of Patent:** **** Oct. 8, 2024**

(54) **BROADCAST SHOCK MOUNT**

(71) Applicant: **Freedman Electronics Pty Ltd**,
Silverwater (AU)

(72) Inventors: **Samuel Dean Trewartha**, Silverwater
(AU); **Chris Woolf**, Silverwater (AU)

(73) Assignee: **Freedman Electronics Pty Ltd**,
Silverwater (AU)

(**) Term: **15 Years**

(21) Appl. No.: **29/850,415**

(22) Filed: **Aug. 19, 2022**

(51) LOC (14) Cl. **14-01**

(52) U.S. Cl.

USPC **D14/229**

(57) **CLAIM**

The ornamental design for a broadcast shock mount, as shown and described.

DESCRIPTION

FIG. 1 is a front perspective view of a broadcast shock mount showing the new design;

FIG. 2 is a rear perspective view of the broadcast shock mount of FIG. 1;

FIG. 3 is a front view of the broadcast shock mount of FIG. 1;

FIG. 4 is a rear view of the broadcast shock mount of FIG. 1;

FIG. 5 is a top view of the broadcast shock mount of FIG. 1;

FIG. 6 is a side view of the broadcast shock mount of FIG. 1;

FIG. 7 is a bottom view of the broadcast shock mount of FIG. 1; and,

FIG. 8 is a left side view of the broadcast shock mount of FIG. 1.

The broken lines to the broadcast shock mount depict portions of the claimed design that form no part thereof; all broken lines form no part of the claimed design.

1 Claim, 2 Drawing Sheets
